GEORGE W. VAN BRUNT, OF HORICON, WISCONSIN.

Letters Patent No. 86,261, dated January 26, 1869.

IMPROVEMENT IN CULTIVATORS.

The Schedule referred to in these Letters Patent and making part of the same.

To all whom it may concern:

Be it known that I, GEORGE W. VAN BRUNT, of Horicon, in the county of Dodge, and State of Wisconsin, have invented a new and improved Cultivator; and I do hereby declare that the following is a full, clear, and exact description of the construction and operation of the same, reference being had to the accompanying drawings, making a part of this specification, in which—

Figure 1 is a longitudinal vertical section.

Figure 2 is a top view.

Figure 3 is a side view, representing a modification of the locking-device.

This invention relates to the mode of attaching cultivator-teeth to the beams or drag-bars, and consists in the employment of two screw-bolts and nuts, in connection with a clamping-plate and a locking-device, the whole being used with a pivoted cultivator-tooth, having a curved arm, which is held in position by the locking-device.

In the drawings—

A is the drag-bar of a cultivator, and

B is the cultivator-tooth, pivoted, at *b*, to the side of the drag-bar, and provided with an arm, B', which, through the greater part of its length, is curved, in the arc of a circle, of which the pivot *b* is the centre.

The tooth, thus formed, is confined to the side of the drag-bar by the bolt *b*, and by another bolt, *b'*, acting in combination with a flat clamping-plate, C, which is screwed against the outside of the shank of the tooth, by means of the bolts, they being headed at one end, and provided with a screw-nut at the other, for this purpose.

The concave edge of the shank or arm B', is provided with one or more notches, *e*, and between the plate C and the arm, held in position by horizontal flanges; on the upper and lower inner edges of the plate, is a sliding stop-bolt, I, which can be pushed forward so that its front end shall enter one of the notches, and lock the tooth B firmly in position.

i is a wedge, which may be employed for the purpose of pushing the bolt I forward, to lock the tooth, in the manner described.

Were the bolt I a rigid, unyielding bar, from its point to the rear end, where the wedge operates it, the tooth would be so firmly locked when the wedge was inserted, that, upon its coming against an immovable obstacle, it would break before it would turn on its pivot to let the cultivator pass the obstacle. I therefore make the bolt in two pieces, *m m'*, separated by a rubber spring, *o*, rounding the end that enters the notch, or making it triangular, so that it will slip from the notch, when

sufficient power is applied to the tooth. Then, by inserting the wedge, as aforesaid, the tooth is locked securely, but not so immovably that it will not yield when in contact with an unyielding obstacle.

The clamping-plate C, and screw-bolts *b b'*, may be, independently of the locking-bolt I, or in connection with it, employed to clamp the shank B to the side of the drag-bar, so as to hold the tooth in the position seen in fig. 1, ordinarily, but let it yield to obstacles.

It is evident that the force required to turn the tooth back on its pivot will vary, accordingly as the bolts *b b'* are screwed up more or less tightly, and as the wedge *i* is driven down, more or less, behind the locking-bolt. It is also evident that, by means of a series of notches on the shank B', or by means of the clamp C *b b'* alone, the tooth can be adjusted at any required inclination.

A stop, *e'*, may be cast, or otherwise formed, on the top of the shank B', so as to strike the bolt *b'*, and prevent the tooth from turning back too far on its pivot.

In the modification shown in fig. 3, the curved arm is fixed to the drag-bar, and the locking-bolt to the tooth, the parts working together for the same purpose as in figs. 1 and 2.

The apparatus employed for attaching and locking the teeth, as above described, is neat in appearance, simple and cheap in construction, and exceedingly perfect in operation. It is confidently believed that its use will, in a single year, ordinarily save all the expense required for its construction and application to any form of cultivator.

Having thus described my invention,

What I claim as new, and desire to secure by Letters Patent, is—

1. The notched and curved arm B', of a pivoted cultivator-tooth, in combination with the locking-bolt I, substantially as and for the purposes set forth.

2. The arrangement of the wedge *i*, rubber or other spring *o*, and parts *m m'* of the bolt I, when the said parts are employed substantially as and for the purposes set forth.

3. The clamping-plate C, in combination with the two bolts *b b'* and the pivoted cultivator-tooth, substantially as and for the purposes set forth.

4. The stop *e'*, arranged upon the curved arm B', and operating, in connection with the clamping-plate C and bolt *b'*, substantially as and for the purpose shown and described.

G. W. VAN BRUNT.
